(57) **CLAIM**

The ornamental design for pipe protector panel, as shown and described.

DESCRIPTION

FIG. 1 is a top perspective view of a pipe protector panel in a flat configuration;

FIG. 2 is a bottom perspective view thereof;

FIG. 3 is a top plan view thereof;

FIG. 4 is a bottom plan view thereof;

FIG. 5 is a top end elevation view thereof;

FIG. 6 is a bottom end elevation view thereof;

FIG. 7 is a left side elevation view thereof;

FIG. 8 is a right side elevation view thereof;

FIG. 9 is a top perspective view of the pipe protector panel in a bent configuration;

FIG. 10 is a bottom perspective view thereof;

FIG. 11 is a top elevation view thereof;

FIG. 12 is a bottom elevation view thereof;

FIG. 13 is a top end elevation view thereof in a bent position;

FIG. 14 is a bottom end elevation view thereof in a bent position;

FIG. 15 is a left side top elevation view thereof;

FIG. 16 is a left side bottom elevation view thereof; and,
FIG. 17 is a top perspective view of the pipe protector shown of use with environmental subject matter.

The broken lines shown in the drawings illustrate portions of the pipe protector panel and environmental that form no part of the claimed design.
